[57] ABSTRACT

The assembly for connection to a swimming pool racing line comprises a floating casing with an inner chamber containing a piston and rod arrangement. In response to the introduction of a fluid within this internal chamber the piston moves to an activated position causing the slideable rod, having one end connected to the swimming pool racing line, to produce tension in the racing line between the respective ends of the swimming pool. The fluid supply enters and exits the inner chamber by simplified valving means adapted for use with a typical garden hose.

SWIMMING POOL RACING LINE TAKE-UP FLOAT ASSEMBLY

BACKGROUND OF THE INVENTION

This invention relates to the field of swimming pool equipment and more particularly to floating racing lines utilized to divide the surface of the swimming pool into separate racing lanes for competition swimming. In order to divide the swimming pool into proper identifiable racing lanes, the racing line must be tight between the respective ends of the pool to prevent any weaving or floating drift of the racing line. Otherwise, the line could interrupt or obstruct the swimmer as he proceeds down the lane.

Swimming pools that are used for competition swimming events as in schools and athletic clubs have fixed rings attached to the ends of the swimming pool to provide a connection for the racing line to be stretched between the opposite ends of the pool. In order to easily connect the racing line to each end of the pool, it is necessary that the line be slightly longer than the distance between the two rings at the ends of the pool. The remaining slack in the line requires tightening in order to prevent any drift of the racing line. Previous devices have utilized turnbuckle type mechanisms which are quite awkward for a coach or manager who is located on the deck of the pool to operate, since he has to turn and twist the line in order to tighten it. Also, some problems are caused by having to twist the line which may damage the line. This same procedure of turning the turnbuckle must be followed in order to again loosen the racing line in order to allow easy removal of the line from the swimming pool. The time spent with installing and removing racing lines in the swimming pool by utilizing the turnbuckle type arrangement is time which can be better spent by the coach or manager in attending to the activities within the swimming pool or with the members of the swimming team.

Other devices have used a hand winch type of arrangement which is awkward and difficult to adjust to the correct tightness, since the locking device is limited. These winch arrangements are especially difficult for one who is on the deck of the swimming pool to operate.

Also, the mechanism utilized in these prior devices for eliminating the slack in the racing line use a connection with the racing line which results in the existence of protrusions which could cause injury to the swimmer if his arm or leg should happen to contact the racing line at that point.

SUMMARY OF THE INVENTION

This invention utilizes a simple casing which floats on the water and contains a slideable piston and piston rod with one end extending through the casing and connected to the racing line. The other end of the casing is connected to the racing line, and a valve is placed in the wall of the casing to permit the introduction of a fluid such as water from a typical garden hose to place hydraulic pressure on the piston within the casing. This pressure will move the piston to an activating position and cause the rod to pull the racing line in a tight position. The swimming pool racing line take-up device is very simple in construction and presents a mechanism which is easy to operate. The actuating time is essen-

tially instantaneous, approximately two seconds, which is quite important as a time saver when considering all the other preparations necessary to operate a swimming race. The swimming coach, having a garden hose available for washing down the deck of the swimming pool, can use the garden hose to operate this invention by simply holding it against the valving member located on the casing and allowing the water to fill the casing enough to provide the requisite tension in the racing line. The garden hose is simply held by hand against the valve member of the casing rather than screwing or rigidly fixing it to the valve member, so that, if the pressure would become too great within the casing, the swimming coach could not maintain or hold the hose against the valve because of the increased pressure. If the hose were rigidly connected to the casing, the pressure may become too great and cause the racing line to be tightened to an extent that the fixtures could be pulled from their mountings on the side of the swimming pool. This arrangement of just allowing the hose to be handheld against the valve on the casing eliminates the need for any type of pressure regulator in order to prevent possible damage to the racing line fixtures.

The racing line take-up device has an additional feature which aids in the prevention of exerting too great a stress on the swimming pool wall fixtures. Since the piston is sealed against the interior surface of the casing, pushing the piston rod a short distance into the casing before applying the hose will cause a small amount of air to enter the casing through the valve. The air will act as a cushion or shock absorber to increased pressure on the swimming pool wall mountings if swimmers sit or stand on the tightened line because the air is compressible while water is not.

The connectors on each end of the casing for attachment to the racing line utilize collet devices which provide a means to insert the end of the racing line thereby covering all exposed ends of the line and eliminating any possible projections which may injure the swimmer.

Another unique feature to this device is that the operator does not need any specific tools to release the fluid within the casing, since a typical pencil or pen can be inserted into the valve mechanism to release the ball check and allow the pressurized water to exit from the casing resulting in a slackening of the racing line.

BRIEF DESCRIPTION OF THE DRAWINGS

FIG. 1 is a perspective view of the hydraulic swimming pool racing line take-up device connected within the racing line which is extended between the two ends of the swimming pool;

FIG. 2 is a cross-sectional view of the racing line take-up device; and

FIG. 3 is a partial cross-sectional view of the racing line take-up showing the valving mechanism.

DETAILED DESCRIPTION OF THE INVENTION

With reference to FIG. 1 the racing line take-up assembly 10 is shown connected to a racing line 12 extended between the two ends 14 and 16 of a typical swimming pool. Also placed along the racing line 12 are a series of float members 18 to maintain the racing line on the surface of the water. The racing line take-up assembly 10 is positioned within the racing line 12 adjacent one end 16 of the swimming pool for proximity to

the deck area 20 to provide easy access for operation by a swimming pool manager or a swimming coach. The racing line take-up device 10 could also be placed adjacent the other end 14 of the swimming pool.

The racing line take-up device 10 is shown in more detail in FIG. 2 and is comprised of a casing or container 22 having an inner chamber or cavity 24. Located within the chamber 24 is a slidable activating rod or shaft 26 which extends through one end 28 of the casing 22. The shaft 26 is sealed within the one end 28 of the casing 22 by O-rings 25. One end 30 of the shaft 26 is connected to the racing line 12 while the other end 32 of the shaft 26 is attached to a piston 34, having a sealing ring 35. The other end 36 of the casing 22 is also connected to the racing line 12. Within the cavity 24 adjacent one end 28 of the casing 22 is a stop member 29 to limit the travel of the piston 34 in that direction. Similarly located within the cavity 24 adjacent the other end 36 of the casing 22 is a stop surface 37 to limit the travel of the piston 34 in that direction. Vent holes 39 are positioned within the other end 36 of the casing 22 in order to relieve any pressure behind the piston 34 to allow it to activate as explained later.

Located within the casing 22 is a valving mechanism 38 comprised of a valve body 40 and a ball check 42 which is biased against the flow channel 44 by a spring 46. The flow channel 44 has a neck portion 48 which is surrounded by an interface member or tapered grommet 50 on the outside surface of the casing 22. Surrounding the casing 22 is a float section 52 to maintain the racing line take-up device 10 buoyant on the water.

The racing line 12 is attached to the racing line take-up assembly device 10 by connectors 54 and 56. These connectors are identical in construction and are comprised of a collet 58 with gripping members 60 which separate apart or close together depending upon the rotation of the collet on the threaded member 62. This provides easy connection of the end 64 of the racing line 12 to the casing 22. Located on one end 30 of the shaft 26 are flat areas 63 to accommodate a wrench to prevent rotation of the device while tightening the connector 54. Flat areas may also be incorporated on the threaded member 62 by using a longer threaded member to allow sufficient space between the connector 56 and the other end 36 of the casing 22. These latter flat areas will receive a wrench to prevent rotation of the device while tightening the connector 56.

Turning to the operation of the racing line take-up assembly 10, reference is made to FIG. 1 where the device 10 is connected within the racing line 12 to provide flexibility in the adjustment of the length of the racing line. The respective ends of the racing line 12 are attached to the hook assemblies 66 which are embedded in the end walls 14 and 16 of the swimming pool. The racing line 12 is slightly longer than the distance between the respective hook assemblies 66 on end walls 14 and 16. After attachment of the racing line 12 to the hook assemblies 66, there is some slack in the racing line 12 which will cause it to drift unevenly on the surface of the water. In order to tighten the line 12 to define specific racing lanes, the racing line take-up assembly 10 is utilized to tighten the line sufficiently to remain in a straight perpendicular orientation to the respective end walls 14 and 16.

The operation of the take-up assembly 10 is shown in more detail in FIG. 2. After the racing line is first at-

tached to the hook assemblies 66, the piston 34 is in the release position, position A shown in phantom, allowing the activating shaft 26 to extend as far as possible out through the end 28 of casing 22 to provide the necessary slack for easy installation of the racing line. When it is desired to tighten the racing line 12, as a first step the piston 34 may be moved away from the stop member 29 slightly to cause some air to be sucked into the cavity 24 to provide a shock absorbing feature which will be explained below. Then a typical or standard garden type hose 68 which is used to wash down the deck of the swimming pool is placed over the tapered grommet 50 and held there by hand. Since the diameter of the smaller end 70 of the grommet 50 is less than the opening of a typical garden hose coupling 71 and since the diameter of the larger end 72 of the grommet 50 is greater than the opening of a typical garden hose coupling 71, the garden hose coupling 71 will rest on the grommet 50 between the respective ends 70 and 72.

Water is induced through the flow channel 44 and forces the ball check 42 downward against the spring 46 to allow water to enter the inner cavity or chamber 24. However, in order for the water to reach the chamber 24 it impinges the contact surface 74 of the piston 34 and forces it in the direction to the left toward the activated positions B and C. The movement of the piston from position A toward position B causes the slidable shaft 26 to also move a corresponding distance which will pull or activate the racing line 12, making it tight and straight. The maximum distance which the piston 34 and the shaft 26 can move is measured by the throw 76 with position C being the extreme position.

Since the take-up float assembly is designed to be utilized in different sized swimming pools the necessary movement of the piston 34 to the left in FIG. 2 will depend upon how much slack is in racing line 12. Because of the varying water pressure available in different locations there would be concern that, if the water forces the piston too far to the left for a particular size swimming pool, the racing line 12 may become so tight that it will tend to pull the hook assembly 66 out of its mounting in the end walls of the pool. Therefore, the ability to simply hold the garden hose over the grommet 50 by hand provides a means where, if the pressure within the chamber 24 becomes too great it will be very difficult or impossible for the user to hold the hose over the grommet 50, eliminating a chance of the racing line 12 becoming too tight for the hook assembly 66. Additionally, the introduction of the small amount of air into the cavity 24 prior to the flow of water from the hose 68 provides a shock absorbing feature, since the air will compress where water will not. Therefore, this small amount of air will help absorb the shock and prevent too great a pull being exerted on the hook assembly 66 if a swimmer sits or stands on the line.

When the swimming coach or swimming pool manager desires to loosen the racing line 12 in order to remove it from the swimming pool, there is no need for any special tool, because a typical writing pencil or pen 78, shown in FIG. 3, which is usually conveniently found, can be inserted down through the flow channel 44, which is large enough for such an item. This forces the ball check 42 down far enough to permit the pressurized water to escape through the channel 44, allowing the piston 34 to move to the right with respect to

FIG. 2, causing a slack to the line 12 in order for it to reach the release position.

What is claimed is:

1. A swimming pool racing line take-up device comprising:

a hollow casing;

a movable member mounted within said casing, one end of said member extending through one end of said casing, said one end of said member connected to said racing line; the other end of said casing being connected to a side of said swimming pool;

means located on said casing for allowing fluid communication between the interior of said hollow casing and an outside fluid supply; and

means attached to said movable member and responsive to said fluid communication for moving said movable member and induce strain in said racing line.

2. A swimming pool racing line take-up device as defined in claim 1 wherein said movable member comprises a slideable rod and wherein said means for moving said rod comprises a piston having a contact surface responsive to the movement of said fluid within said casing.

3. A swimming pool racing line take-up device as defined in claim 1 wherein said means for allowing fluid communication between the interior of said hollow casing and an outside fluid supply comprises:

a valve body, defining a flow channel; a check valve adjacent said flow channel; and an interface member surrounding the exterior portion of said valve body.

4. A swimming pool racing line take-up device as defined in claim 3 wherein said interface member is a tapered grommet adapted to mate with the end of a typical garden hose.

5. A swimming pool racing line take-up device as defined in claim 4 wherein said tapered grommet has one end smaller than a coupling on said garden hose and the other end larger than the coupling on said garden hose, so that said mating of said garden hose occurs between said ends of said grommet.

6. A swimming pool racing line take-up device as defined in claim 3 wherein said check valve comprises a ball check biased against said flow channel by a spring.

7. A swimming pool racing line take-up device as defined in claim 3 wherein said flow channel is of sufficient size to receive a typical writing instrument to release the check valve to allow the fluid to escape.

8. A swimming pool racing line take-up device as defined in claim 1 wherein said one end of said movable member comprises a collet mechanism for receipt of an end of said racing line.

9. A swimming pool racing line take-up device as defined in claim 1 wherein the other end of said casing has a collet mechanism for receipt of an end of said racing line.

10. A swimming pool racing line take-up device as defined in claim 1 wherein said means for moving said movable member comprises a piston which moves said racing line to an activated position, tightening said racing line, when said fluid enters said casing, and moves said racing line to a release position when said fluid exits said casing, loosening said racing line.

11. A swimming pool racing line take-up device comprising:

a casing having an interior cavity; means mounted on said casing for allowing the flow of a liquid into said cavity;

a slideable shaft having one end extending through one end of said casing, said one end of said slideable shaft connected to said racing line; and

a piston member mounted on the other end of said shaft, said piston member slideable within said cavity and responsive to said flow of said liquid, contact between said piston member and said cavity being air tight, movement of said piston member away from said one end of said casing causing air to be introduced into said cavity, said air being compressed by said flow of said liquid resulting in said air acting as means for absorbing a shock caused by a strain induced on said racing line.
